UNITED STATES PATENT OFFICE.

JOHN P. BAIRD, OF WHITESTONE, NEW YORK.

CHAFE-IRON FOR VEHICLES.

SPECIFICATION forming part of Letters Patent No. 759,849, dated May 17, 1904.

Application filed August 25, 1903. Serial No. 170,687. (No model.)

To all whom it may concern:

Be it known that I, JOHN P. BAIRD, a citizen of the United States, residing at Whitestone, Long Island, in the county of Queens 5 and State of New York, have invented certain new and useful Improvements in Antichafe Attachments for Vehicles, of which the following is a specification, such as will enable those skilled in the art to which it appertains to make and use the same.

The object of this invention is to provide an improved antichafe device for buggies, wagons, and other vehicles, which is designed to prevent the wheels of the vehicle from chafing, wearing, or otherwise injuring the sides 15 of the body or framework or other parts of the vehicle in the operation of turning the same. It is a well-known fact that in the operation of turning a vehicle of the class specified the front wheels thereof frequently 20 come in contact with the sides of the body, framework, reaches, or other parts of the vehicle and chafe, wear, or cut the same and frequently do great injury, and one of the objects of this invention is to prevent this and 25 also to provide an antichafe device for the purpose specified which will also serve as an antifriction and antirattler device and which may be changed at will to adapt it to wheels 30 with either metal or rubber tires.

The invention is fully disclosed in the following specification, of which the accompanying drawings form a part, in which the separate parts of my improvement are designated 35 by suitable reference characters in each of the views, and in which—

Figure 1 is a partial perspective view of an ordinary buggy provided with my improved attachment; Fig. 2, a side view of the attachment detached from the buggy; Fig. 3, a cross-section on the line 3 3 of Fig. 2; Fig. 4, a section on the line 4 4 of Fig. 3; and Fig. 5, a section on the line 5 5 of Fig. 2, but showing a modification.

In the practice of my invention I provide 45 an oblong support *a*, having a vertically-arranged plate *a*² and a horizontal and backwardly-directed support *a*³, and the plate *a*² is provided with screw-holes *a*⁴, whereby the 50 attachment may be secured to the bottom of

the side or sides of a buggy-body, and it will be apparent that said attachment may be secured to any desired part of a vehicle with which the front wheels in turning the vehicle come in contact.

The support *a* is segmental in cross-section and is provided at each end with tubular members *a*⁵, each of which is open at its inner end and one of which is open at its outer end and closed by a screw-threaded plug *b*, having a 55 knob or handle *b*².

In the form of construction shown in Figs. 3 and 4 the support *a* is provided in the inner surface thereof with a longitudinal recess *a*⁶, in which is placed a curved plate-spring *c*, and 65 in practice I provide a cylindrical bearing *d*, which is passed into and through the tubular members *a*⁵, as shown in Fig. 4, and secured therein by the screw-threaded plug *b*.

In practice the cylindrical bearing *d* is made 70 of steel if the vehicle is provided with metal or steel tires; but if the vehicle is provided with rubber tires the said cylindrical bearing will be made of hard rubber, hard wood, or some similar material.

It will be observed that the tubular members *a*⁵ cover only the ends of the cylindrical bearing *d*, and the support *a* is open at the outer side and at the top and bottom thereof, and the distance between the tubular members *a*⁵, which hold the cylindrical bearing *d*, is considerable, and the attachment is so placed that the front wheel or wheels will always strike the cylindrical bearing *d*. The spring *c* in the form of construction shown in Figs. 85 3 and 4 presses onto the cylindrical bearing *d* and prevents the too-free movement and the consequent rattling thereof, and the said cylindrical bearing being provided at the back with a support throughout its entire length 90 cannot be broken by the wheel or wheels coming in contact therewith and pressing thereon. The cylindrical bearing *d* is also free to turn in the members *a*⁵. When turning, the wheel or wheels press thereon, and the friction is thus largely reduced.

In the form of construction shown in Fig. 5 a spiral spring *e* is placed in the tubular member *a*⁵ opposite the screw-threaded plug *b*, and when the said plug is secured into position it 100

forces the cylindrical bearing d against the said spring, and this spring prevents the too-free turning and rattling of said cylindrical bearing.

5 My invention is not limited to the exact form of the plates a^2 and a^3 , with which the support a is provided; but said plates may be of any desired width, and the plate a^2 may be ornamental in form, and various changes in 10 and modification of the construction herein described may be made without departing from the spirit of my invention or sacrificing its advantages.

Having fully described my invention, what 15 I claim as new, and desire to secure by Letters Patent, is—

1. An antichafing device for vehicles comprising an oblong support segmental in cross-section at the outside thereof and provided 20 with a longitudinal recess and a spring placed therein, said support being also provided at its ends with tubular end members, and a cylindrical bearing adapted to be secured in said end members and to bear throughout its length

on said support and to press against said 25 spring, substantially as shown and described.

2. An antichafing device for vehicles comprising an oblong support segmental in cross-section at the outside thereof and provided with a longitudinal recess and a spring placed 30 therein, said support being also provided at its ends with tubular end members, and a cylindrical bearing adapted to be secured in said end members, and to bear throughout its length on said support and to press against said 35 spring, one of said tubular end members being provided with a screw-threaded plug for holding said cylindrical bearing in position, substantially as shown and described.

In testimony that I claim the foregoing as 40 my invention I have signed my name, in presence of the subscribing witnesses, this 24th day of August, 1903.

JOHN P. BAIRD.
